(57) CLAIM

I claim the ornamental design for a CD/DVD player and radio, as shown and described.

DESCRIPTION

FIG. 1 is a side view of the CD/DVD player and radio showing my new design;

FIG. 2 is a front view thereof;

FIG. 3 is a side view thereof;

FIG. 4 is a bottom view thereof; and,

FIG. 5 is a front and side perspective view thereof.

The broken lines in FIGS. 1-5 are for illustrative purposes only and form no part of the claimed design.
